UNITED STATES PATENT OFFICE.

WILLIAM J. SMITH, OF WATERBURY, CONNECTICUT, ASSIGNOR TO WATERBURY CLOCK CO., OF WATERBURY, CONNECTICUT, A CORPORATION.

BUTT-HINGE.

1,271,235.

Specification of Letters Patent.

Patented July 2, 1918.

Application filed September 11, 1917. Serial No. 190,738.

To all whom it may concern:

Be it known that I, WILLIAM J. SMITH, a subject of the Emperor of Austria, residing at Waterbury, in the county of New Haven 5 and State of Connecticut, have invented a new and useful Improvement in Butt-Hinges; and I do hereby declare the following, when taken in connection with the accompanying drawings and the characters of 10 reference marked thereon, to be a full, clear, and exact description of the same, and which said drawings constitute part of this application, and represent, in—

Figure 1 a broken view in elevation showing my improved hinge as in use.

Fig. 2 a view thereof in transverse section, showing how the offsetting knuckle of 20 the hinge effects the clearance of the molding-strip on the door from the door-jamb when the door is opened.

Fig. 3 a broken view in inside elevation of the door and door-jamb, showing the door in its closed position.

Fig. 4 a broken edge view of the door and 25 door-jamb, showing the door in its open position.

Fig. 5 a detached perspective view of the hinge in its open position.

My invention relates to an improved 30 hinge designed for use in situations where, for the sake of appearance, it is desirable to practically conceal the hinge, the object being to produce at a low cost for manufacture, a simple, light and effective hinge of 35 this character.

With these ends in view, my invention consists in a hinge having certain details of construction as will be hereinafter described and pointed out in the claim.

40 In carrying out my invention as herein shown, I form the lower edge of the leaf 2 of the hinge with a flange 3 turned inwardly at a right angle to its plane, and having its inner end extended to form a knuckle 4. In 45 the same manner, I form the upper end of the leaf 5 of the hinge with a flange 6 turned outwardly at a right angle to its plane and having its inner end extended to form a knuckle 7, overlapping the knuckle 4 and secured thereto by a pintle 8. By bending the

flanges 3 and 6 in opposite directions, as described, the leaves 2 and 5 are made rights and lefts. The said leaves 2 and 5 have countersunk screw holes 9 for the reception of the screws 10 by means of which they are 55 respectively secured to the edge of the door-jamb 11 and to the edge of the door 12, as clearly shown in Fig. 3. As shown in Fig. 1, the door is provided upon its inner edge with a bead or molding-strip 13 secured in 60 place by brads 14 and overhanging the joint 15 between the door and the jamb. This bead is formed with a transverse slot 16 into which the offsetting knuckles 4 and 7 enter. These knuckles are offset to such an extent 65 from the leaves 2 and 5, that the bead 13 clears the jamb 11 as the door is opened.

By forming the adjacent ends of the respective leaves of the hinge with flanges turned therefrom in opposite directions and 70 offset toward each other to form overlapping knuckles joined by a pintle, I secure a hinge which, when applied, is invisible except for the very narrow width of the 75 knuckles which project outward from the door and jamb to which the hinge is applied. Now these knuckles may be almost entirely concealed from the ordinary observer, if a bead or molding-strip such as 13, is applied to the door, and formed with a slot 16 for 80 the reception of the knuckles. My improved hinge as thus constructed is extremely simple and as efficient as any ordinary hinge. It is particularly adapted for use in hanging the doors of clock cases or other light 85 cabinets. Of course the bead is not essential to the use of the hinge, being merely ornamental in its office and not functional except in so far as it prevents the knuckles from being hit or bent.

90 I claim:—

A butt-hinge for doors, comprising complementary right and left hand axially parallel leaves perforated for the reception of fastening-screws and having their adjacent 95 ends bent transversely in opposite directions to form flanges which are extended toward each other beyond the adjacent edges of the said leaves and terminate in overlapping knuckles which are united by a pintle, 100

whereby when the hinge is closed, the said flanges are registered and their knuckles concealed in a transverse slot in a bead or molding-strip applied to the door in position to cover the joint or "crack" between the door and door-frame.

In testimony whereof, I have signed this
